METHOD AND APPARATUS FOR HYDRAULIC DREDGING

Filed Dec. 26, 1923

UNITED STATES PATENT OFFICE.

OSCAR C. GOERIZ, OF OAKLAND, CALIFORNIA.

METHOD AND APPARATUS FOR HYDRAULIC DREDGING.

Application filed December 26, 1923. Serial No. 682,701.

To all whom it may concern:

Be it known that I, OSCAR C. GOERIZ, a citizen of Germany, residing at Oakland, in the county of Alameda, State of California, have invented a new and useful Method and Apparatus for Hydraulic Dredging, of which the following is a specification in such full and clear terms as will enable those skilled in the art to construct and use the same.

This invention relates to an improvement in hydraulic dredging equipment, one object of which is to produce a dredge which will be more efficient than the present installations because better adaptable to wide ranges in the lengths of discharge pipe, as well as to the wide variety of materials dredged from the bottom of water-ways.

The equipment described herein makes use of appropriate and adjustable velocities in the suction pipe to lift only such an amount of solids to the dredge pump as can be transferred to the place of deposit with the velocity obtainable in the particular discharge pipe for the prevailing capacity of the dredge pump.

It is understood by those skilled in the art that the hydraulic equipment of a suction dredge comprises four principal parts, to produce and transport a mixture of water and solids: First, a cutter or agitator; second, an inclined suction pipe; third, a centrifugal dredge pump; fourth, a long, substantially horizontal delivery or discharge pipe, which may, at times, have short, steeply inclined sections.

It is apparent from mechanical constructions that the solids contained in the mixture are carried along by friction and impact between the water and solids, and that the water in such a mixture travels somewhat faster than the solids. For the transportation of fine material, such as mud, or light materials such as peat, there is required a very small difference in speed between the water and transported particles, but such materials as are coarse and of high specific gravity are transported with difficulty. The latter materials require considerable difference of velocity to transport them, and this fact renders it necessary to use large absolute velocities of the water and mixture.

The present invention provides means to

remove an appropriate quantity of water from the mixture after the solids have been brought above the inclined portion of the suction pipe thereby making use of a large quantity of water at a high velocity, while the materials are being lifted up the steeply inclined pipe, whereas the remaining smaller quantity of water or lesser velocity is ample to carry the solids through the practically horizontal discharge pipe.

The suction pipe may be of equal diameter with the discharge pipe, but usually a larger diameter suction pipe will be made use of, since that is the way dredges are commonly equipped. The latter feature will allow the use of the ordinary dredge without the auxiliary equipment when the delivery pipe is extremely short and the pump capacity so big that a rich mixture of solids can be handled through the ample suction pipe, but it must be understood that without the proposed auxiliary equipment, such a dredge will not work most economically if the discharge pipe is long when the pump capacity falls off and the velocity in the suction pipe becomes small.

Another object of the invention is to improve the discharge conditions in the discharge pipe of a hydraulic dredge.

From the foregoing it will be apparent that the same conditions obtaining in the suction pipe will be observed in any section of the discharge pipe when it is necessary to force the discharge up a short steep incline. This condition is met by reducing the size of the discharge pipe to the top of the incline, and widening the diameter to the original size by means of a long conical piece interposed between the two.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a side elevation of a dredge showing this invention applied thereto,

Fig. 2 is a view in elevation of the auxiliary pump and settling chamber, the latter being shown in section on the line 2—2, Fig. 1.

Fig. 3 is a view of a portion of the dis-

charge pipe line showing the manner of overcoming sudden rises in the line.

The numeral 1 indicates a barge on which there is mounted a motor 2 directly connected to the pump 3, which pump has the horizontal suction pipe 4 on the end of which is the pivoted suction pipe 5 with the cutter or agitator 6 at its lower end.

10 A boom 7 carrying a block 8 over which a cable 9 passes is used for the support of the suction pipe at the proper level. The cable also passes through a pulley 10 on the lower end of the suction pipe to support the latter and to raise or lower it at will. The 15 boom 7 is supported by the cable 11.

Between the pump 3 and the upper end of the pipe 5, there is installed a section of pipe 12 which opens on the top into a wide box 13, a kind of classifier or spitzkasten, which 20 has a series of reversely positioned baffle plates 14, 15, 16 therein, said plates being for the purpose of preventing the heavy materials from passing up into the settling chamber. At the upper end of the classifier 25 is a suction pipe 17 which extends to and is connected with the auxiliary pump 18. The pump 18 is operated by any suitable motor 19 and it has a flaring underwater discharge pipe 19' to discharge the water with the 30 least possible loss of residual energy.

The main pump 3 has discharge pipe 20 leading to some remote place of discharge, said pipe being frequently as long as a mile or even two miles in some instances.

35 In figure 3 the discharge pipe 20 is shown at a point where a steep bank must be climbed. Here the pipe is provided with a tapering nozzle 25, a section 26 of smaller diameter, a long reversely tapering nozzle 26' and the final discharge pipe 27. The smaller inclined pipe causes an increase in water velocity and effectively lifts the materials. It is also advisable to have the 40 rising portions of the pipe placed at an inclination less than the angle of repose for the materials being handled, because whenever the pumping operations stops, all the 45 materials in the section 26 tends to slide back to the nozzle 25, thereby clogging the 50 pipe.

In operation the speed within the suction pipe 5 is made high enough to carry the desired materials up the incline whatever it 55 may be, and the pump 18 is operated to remove the proper volume of comparatively clear water at a point where the suction pipe is substantially at the level of the main pump 3. The settling chamber prevents any of the heavier materials from passing 60 into the auxiliary pump, and the smaller volume of enriched mixture can then be forced through the smaller pipe 20 at a sufficient velocity to carry said materials. The removal of the surplus water by the

pump 18 results in a considerable reduction 65 in the friction loss of the pipe 20 since less water is transported.

What I claim is as follows, but modifications may be made in carrying out the invention shown in the drawings and in the 70 above particularly described form thereof, within the purview of the invention as defined by the annexed claims.

1. A method of operating hydraulic dredges which consists in drawing a mixture 75 of solids in water up an inclined suction pipe, then removing a portion of the clearer water, and finally forcing the remaining water and solids through a smaller discharge pipe to a place of deposit. 80

2. A method of operating hydraulic dredges which consists in drawing solid materials suspended in water up an inclined suction pipe, passing the mixture through a settling chamber, withdrawing and discharging some of the clearer water from 85 said chamber at the dredge level, and finally forcing the remaining mixture through a smaller discharge pipe to a place of deposit. 90

3. In a suction dredge, the combination 95 of a suction pipe, a centrifugal pump, a discharge pipe, and means to remove some of the water from the system at the dredge. 100

4. In a suction dredge, the combination 105 of a suction pipe, a centrifugal pump connected thereto, a discharge pipe therefor, a hydraulic separator through which the mixed water and solids pass, and means to remove from the system a portion of the water at the dredge. 110

5. In a suction dredge, the combination 115 of a suction pipe, a centrifugal pump connected thereto, a discharge pipe therefor, a hydraulic classifier through which the mixed materials pass, and means to remove some of the clearer water from said classifier at the dredge. 120

6. In a suction dredge, the combination 125 of a suction pipe, a centrifugal pump connected thereto, a hydraulic classifier through which the materials pass to said pump, a second pump to remove some of the clearer water from said classifier, and a discharge pipe for the main pump. 130

7. In a suction dredge, the combination 135 of a suction pipe, a centrifugal pump connected thereto, a discharge pipe therefor, a hydraulic classifier included in a horizontal portion of the suction pipe at about the level of said pump, and a second pump to remove some of the clearer water from said classifier. 140

8. In a hydraulic dredge, the combination 145 of a suction pipe, a suction pump connected thereto, a discharge pipe, an auxiliary pump to directly discharge some of the water passing into the suction pipe and means to vary the volumetric capacity of the second pump 150. 155

in proportion to the capacity of the second pump.

9. In a suction dredge the combination of a suction pipe, a pump connected thereto, 5 a discharge pipe having its steeply inclined portions of less diameter than its horizontal portions, reversely placed tapered sections

being provided near each end of the smaller inclined portion.

In testimony whereof I have hereunto 10 set my hand this 18th day of December A. D. 1923.

OSCAR C. GOERIZ.
